UNITED STATES PATENT OFFICE

NELSON B. HENRY, OF DALLAS, TEXAS, ASSIGNOR TO THE MURRAY COMPANY, OF DALLAS, TEXAS, A CORPORATION OF TEXAS.

TRAMPER FOR COTTON-PRESSES.

1,212,637.

Specification of Letters Patent. Patented Jan. 16, 1917.

Application filed November 27, 1915. Serial No. 63,712.

To all whom it may concern:

Be it known that I, NELSON B. HENRY, a citizen of the United States, residing at Dallas, in the county of Dallas and State of Texas, have invented certain new and useful Improvements in Trampers for Cotton-Presses, of which the following is a specification.

My invention has relation to an improvement in trampers for cotton presses and in such connection it relates more particularly to the construction and arrangement of the mechanism for operating the trumper foot. In devices of this kind it has been almost universally the custom to adapt the operating mechanism for the trumper to the motive power generally used, to wit, steam. There has not, to the best of my knowledge, been devised an operating mechanism for trampers of simple construction capable of use with any motive power whether steam, gas or gasolene engine or electric motor.

The provision of means capable of operating the presser or trumper foot, said means capable of being operated from any source of power constitutes one of the objects of my present invention. In devices of this kind the mechanism for operating the trumper should be self controlling in that the distance traveled in the elevation or lowering of the trumper foot is automatically limited by the operating mechanism itself. Further, while the operating mechanism is constantly under the control of the attendant it is desirable that the operating mechanism shall automatically correct any mistake of the operator due to his negligence or carelessness in his manipulation of the mechanism.

The provision of means for automatically limiting the stroke of the trumper foot as well as the provision of means whereby in case of carelessness or negligence the operating mechanism be not properly operated, said mechanism will automatically correct the mistake, constitute further objects of my invention.

The nature and scope of my invention will be more fully understood from the following description taken in connection with the accompanying drawings forming part hereof, in which,

Figure 1, is a front elevational view of a trumper for cotton presses embodying the

main features of my invention; Fig. 2 is a front elevational view, enlarged, of the operating mechanism for the trumper; Fig. 3, is a side elevational view of Fig. 2; Fig. 4, is a transverse, vertical, sectional view taken on the line 4—4 of Fig. 3; Fig. 5, is a cross sectional view taken on line 5—5 of Fig. 3; and Fig. 6, is a detail view in section of the drive mechanism.

Referring to the drawings, 1 represents the trumper foot which is secured to and carried by the lower end of a vertically arranged frame 2. In the preferred construction the frame 2 consists of two metallic beams which slide up and down in guides 3, projecting from brackets 4, supported by a platform or floor 5, which platform or floor constitutes the support for the driving mechanism for the apparatus. At either end of the frame 2 is a bearing 6 and 7, the bearing 6 supporting a sprocket 8 and the bearing 7 supporting the sprocket 9. The two sprockets 8 and 9 are arranged preferably between the two beams constituting the frame 2.

In the stationary frame-work of which brackets 4 constitute a part is mounted the shaft 10 to which the main driving gear 11 is secured. The shaft 10 also carries a sprocket 12. Below the gear 11 in the framework is supported an idler sprocket 13. To the right side of the framework is secured a bar 14 having at either end a tensioning or take-up device 15 of any desired construction. A chain 16 is secured at one end to one end of the bar 14, then passes over the sprocket 8 at the top of the reciprocating frame 2 then extends downward under the idler sprocket 13, then over the sprocket 12 of shaft 10, then under the sprocket 9 at the bottom of the frame 2 and the other free end of the chain is then secured to the take-up device 15.

When gear wheel 11 revolves in one direction, say clock-wise, (Fig. 4) the lower part of the chain 16 is wound up and the upper part of chain 16 unwound to thereby raise the frame 2 and presser foot 1. However, when the gear 11 is revolved in the reverse direction the upper part of chain 16 is wound up and the lower part unwound to thereby depress frame 2 and trumper foot 1.

The rotation of the gear 11 in either direction is accomplished as follows: In mesh with gear 11 is a pinion 17 keyed or other-

wise secured to a shaft 18. Adjacent to pinion 17 but back of the same is a pinion 19 having a sleeve 20 surrounding the shaft 18 but loose thereon. The sleeve 20 is keyed or locked to a driving pulley 21, turning loosely on shaft 18. The shaft 18 is keyed or locked to a driving pulley 22 and intermediate of the two pulleys 21 and 22 is a third or idler pulley 23 running idle on shaft 18. When shaft 18 is driven by its pulley 22 the pinion 17 is rotated to rotate the gear 11 in one direction. When the driving pulley 21 is driven as hereinafter described the pinion 19 is driven. This pinion 19 meshes with a pinion 24 which is in gear with the main gear 11 and serves to turn the said gear in a direction opposite to that in which pinion 17 turns said gear. The main gear 11 still being in mesh with pinion 17, the shaft is rotated in reverse direction.

A belt 30 operated by belt-shifter 31 is adapted to be shifted from the intermediate pulley 23 to pulley 21 or pulley 22 when the lever 32 of the belt shifter 31 is either pushed inward or pulled outward by the operator. To prevent the shaft 18 from continuing to rotate after the belt has been shifted to the idle pulley 23 to stop the operation of the machine, there is secured to the end of the shaft a brake disk or pulley 33, inclosed between the two pivoted brake arms 34, the free ends 35 of which are connected by a stout spring 36. The belt shifter lever 32 is fastened at its upper end to a rock shaft 37 which traverses both brake arms 34 and is provided between said arms with the cam projections 38 operating upon the free ends 35 of said brake arms 34. Thus if lever 32 is pulled out or pushed inward to shift belt 30 to pulley 22 or 21, the rock-shaft 37 is turned so that its cams 38 separate the arms 34 against tension of spring 36 but when the lever is in position to shift belt to idle pulley 23 then the rock-shaft 37 is turned so that its cams 38 permit the arms 34 to tightly clamp the brake pulley 33 under tension of said spring 36, and thus stop the rotation of shaft 18 instantly.

In the operation of the machine as heretofore described, the operator standing in front of the machine manipulates the lever 32 as required. If for any reason he releases the lever, it immediately assumes a position in which belt shifter 31 brings the belt 30 to the idle pulley 23, being thrown to said position by the action of the brake arms and spring. Sometimes the operator, being negligent or careless, will hold the lever 32 too long in the upward or downward movement of the frame 2 and trumper foot 1. If this were not automatically prevented serious injury and damage to the mechanism would result. In my present machine I pro-

vide means whereby at the extreme upward or downward movement of the machine, the frame 2 automatically operates the belt shifter to shift the belt to the idle pulley to stop the machine or if for any reason the brake fails to stop the movement of frame, to shift the belt to the other driving pulley to reverse the movement of frame and trumper foot. To accomplish this between the beams constituting the frame 2 at the top and bottom thereof, are secured the two cam plates or frames 40 and 41. The upper of these plates 40 has a cam surface 42 designed as the frame 2 descends to throw a lug 50 on the belt shifter link 51 first inward to bring the belt shifter opposite the idle pulley 23 and then still farther inward, as the frame 2 descends, to bring the belt shifter opposite pulley 21 to reverse the movement of gear 11 and frame 2. The cam surface 43 of lower plate 41 is arranged oppositely to the surface 42 of plate 40 being designed as the frame 2 ascends to its extreme upward position, to throw lug 50 and link 51 first outward to bring the belt from pulley 21 to idle pulley 23 and then still farther outward, if the frame 2 continues to move, to reverse the movement of gear 11 and frame 2.

Having thus described the nature and objects of my invention, what I claim as new and desire to secure by Letters Patent is,—

1. In a trumper for cotton presses, a trumper foot, a frame carrying said foot, a fixed framework wherein said frame is adapted to reciprocate, a chain arranged on said frame and having its ends secured to the fixed framework combined with means for winding and unwinding said chain on said frame to thereby reciprocate said frame in the fixed framework.

2. In a device of the character described, a frame, a sprocket arranged at the top, and a sprocket arranged at the base of said frame, an intermediate sprocket, a chain carried over the top sprocket, under the bottom sprocket and over the intermediate sprocket, a fixed framework in which the frame is arranged to reciprocate, a means for securing the ends of the chain to said fixed framework and a means for winding and unwinding the chain on the frame to thereby elevate and depress said frame in the fixed frame-work.

3. In a device of the character described, a fixed frame-work, a frame carrying the trumper foot and arranged to reciprocate in the frame-work, a chain arranged to reciprocate the frame, said chain having its ends secured to the fixed frame-work, a gear controlling the operation of the chain and a driving mechanism arranged to drive the gear alternately in reverse directions.

4. In a device of the character described,

a trumper foot, a frame carrying the trumper foot, a fixed frame work wherein said frame is adapted to reciprocate, a chain arranged on said frame and having its ends secured to the fixed frame work, a means for winding and unwinding said chain on said frame to thereby reciprocate said frame in the fixed

frame work, in combination with means carried by said frame and adapted at the limit of either stroke of said frame to stop the movement of said chain operating means.

In testimony whereof I have signed my name to this specification.

NELSON B. HENRY.
